DYNAMO-ELECTRIC MACHINE

John H. Blankenbuehler, Edgewood, Pa., assignor
to Westinghouse Electric & Manufacturing
Company, East Pittsburgh, Pa., a corporation
of Pennsylvania

Application June 15, 1935, Serial No. 26,871

32 Claims. (Cl. 171—227)

5 My invention relates, generally, to dynamo-electric machines, and it has particular relation to a dynamo-electric machine of the cross-field type suitable for use in arc welding and the like, and which is an improvement over the dynamo-electric machine disclosed in my Patent No. 1,979,665, issued November 6, 1934.

10 The object of my invention, generally stated, is to provide a dynamo-electric machine which shall be simple and efficient in operation, and which may be readily and economically manufactured.

15 An important object of my invention is to provide for regulating the output of a cross-field generator over a wide range of operation.

20 Another important object of my invention is to provide for stabilizing the operation of a dynamo-electric machine of the cross-field type when it is operating in the low output range.

25 Still another important object of my invention is to provide for reducing the cost of manufacture of a cross-field generator by employing parts which require little or no machining.

30 Another object of my invention is to provide a field pole having two types of laminations, one type forming a part of the pole neck and the pole shoe, the other type forming only a part of the pole shoe.

35 Still another object of my invention is to provide a fulcrum for adjustable magnetic shunt members by means of a special configuration of the pole laminations.

40 Another object of my invention is to provide a magnetic circuit connecting the field poles of a cross-field generator comprising a pair of oppositely disposed sets of laminations inside of a cast frame, each set comprising laminations of substantially the same width and length.

45 Still another object of my invention is to provide for simultaneously regulating the position of both magnetic shunt members which are disposed on opposite sides of the armature of a cross-field generator for variably bridging the field poles to correspondingly adjust the output of the generator.

50 A further object of my invention is to provide for indicating the output capacities of a cross-field generator which correspond to various positions of magnetic shunt members that are employed for regulating its output capacity.

55 Still another object of my invention is to provide for increasing the reactance of the output circuit of a cross-field generator when the regulating magnetic shunt members are adjusted for operating the machine in the lower output range.

Another object of my invention is to provide an auxiliary magnetic shunt member carried by and magnetically insulated from the regulating shunt members of a cross-field generator for reducing the reluctance of the magnetic circuit surrounding one of the field windings by bridging the field pole to auxiliary field poles when the machine is adjusted to operate in the lower output range. 5

Other objects of my invention will, in part, be 10 obvious and, in part, appear hereinafter.

My invention, accordingly, is disclosed in the embodiment hereof shown in the accompanying drawings, and comprises the features of construction, combination of elements and arrangement of parts, which will be exemplified in the 15 construction hereinafter set forth and the scope of the application of which will be indicated in the appended claims.

For a more complete understanding of the 20 nature and scope of my invention, reference may be had to the following detailed description, taken in connection with the accompanying drawings, in which:

Figure 1 is a view in side elevation of the 25 generator of a motor-generator set, the portion showing the motor being partly broken away since it forms no part of this invention;

Fig. 2 is a sectional view showing the internal construction of the cross-field generator, and in 30 addition, the output circuit connections are also diagrammatically illustrated;

Figs. 3 and 4 are views, respectively, in side and end elevation of an auxiliary pole piece;

Fig. 5 is a sectional view taken along the line 35 V—V of Fig. 2;

Fig. 6 is a plan view of an indicating dial;

Figs. 7 and 8 are views in side elevation of different types of laminations which are used to 40 form the main pole pieces; and

Fig. 9 is a perspective view showing the arrangement of the laminations which are used to provide the magnetic circuits between the main field poles.

Referring now particularly to Fig. 1 of the 45 drawings, the reference character 10 designates, generally, the frame of the generator. The particular construction of the frame 10 and its arrangement in conjunction with the frame for the motor which is employed to drive the generator, are set forth in my Patent No. 2,094,344, issued September 28, 1937, and assigned to the assignee of this application. 50

As illustrated in Fig. 2 of the drawings, the frame 10 is generally circular in shape and it is 55

of cast construction, in order to reduce the cost thereof when it is manufactured in quantity lots. It will be understood, however, that other types of frame construction may be employed such as 5 welded construction. Since the frame 10 is of relatively low magnetic permeability, it is desirable to provide a magnetic circuit inside of it, which will serve as a path for the magnetic flux and have a minimum of reluctance. Furthermore, it is desired to reduce the flow of eddy currents due to rapid flux changes. For these purposes, an inner frame is provided, which comprises 10 two sets of laminations 11.

As illustrated in Fig. 9 of the drawings, the 15 laminations 11 may all be of substantially the same length and width. It is, therefore, possible to employ standard punchings to make up the sets of laminations 11. Although only four laminations are shown, it will be understood that 20 a greater or a lesser number may be employed. For example, in a generator of this type which I have constructed, I have employed eight laminations in each set.

It will be observed in Fig. 2 that the sets of 25 laminations 11 are oppositely disposed and that they are secured inside of the outer frame 10 by means of bolts 12, which are positioned in suitably threaded openings in bosses 13 integrally cast with the outer frame 10. It will also be 30 observed that the opposed ends of the sets of the laminations 11 are stepped, due to the fact that the individual laminations are of the same length and are curved to form an arc of a cylinder when they are positioned within the outer 35 frame 10.

The generator is provided with main field poles 14 and 15 which are secured to the outer frame 10 by means of bolts 16. It will be observed that the main poles 14 and 15 are positioned in engagement with the stepped ends of the sets of 40 laminations 11, which are positioned between the ends of the poles 14 and 15 and bosses 17 which are cast integrally with the outer frame 10. Due to the fact that the magnetic flux flows from 45 the sets of laminations into or out of the main poles 14 and 15, depending upon their polarities, and does not flow from one of the sets of laminations to the other, it is unnecessary that a complete ring of magnetic structure should be provided inside of the outer frame 10 to form the 50 inner frame. Such a construction would be provided if the laminations forming the sets 11 were continuous and formed a continuous ring or spiral. Such a construction, however, would be 55 expensive since laminations of the length required are not feasible or commercially available for standard sizes of generators. Furthermore, it would be necessary to provide openings for the bolts 16, which are unnecessary in the construction 60 which I have provided.

Each of the main poles 14 and 15 has a pole neck 18 and a pole shoe 19. Since the main flux of a generator of the cross-field type is present in the pole shoes 19, it is essential that a suitable 65 magnetic circuit be provided having a sufficiently low reluctance to permit the required flux to flow. Due to the fact that only a relatively small amount of flux flows through the pole necks 18, it is unnecessary that they be of large cross-sectional area. Furthermore, when a pole neck 18 is provided of minimum size, the dimensions of the series field windings positioned therearound may be considerably reduced. As a result, the 70 cost of the construction is correspondingly 75 reduced.

In order to provide the required cross-sectional area for the various portions of the field poles 14 and 15, I have provided for constructing them of two types of laminations which are shown in Figs. 7 and 8. In Fig. 7, a lamination 20 is illustrated, 5 which forms only a part of the pole shoe 19. In Fig. 8 a lamination 21 is shown, which forms not only a portion of the pole shoe 19, but also forms the pole neck 18. It will be understood that the field poles are formed by stacking the laminations 20 and 21, the laminations 21 being stacked centrally in the pole, while the laminations 20 are stacked at the ends thereof. In one modification of a field pole of this type, I have employed sixty-five laminations of the type shown in Fig. 8, 10 and seventy-eight laminations of the type shown in Fig. 7, thirty-nine of these being disposed on each end of the laminations shown in Fig. 8. In order to hold the laminations in stacked relation, they are provided with punched holes 22, 15 through which rivets may be placed.

The laminations 20 and 21 are provided with cut-out portions 23, in which commutating windings 24 may be positioned. Clips 25, comprising pieces of soft steel, are positioned on the outside laminations 20 of the field poles and are bent around the commutating windings 24, as 20 illustrated, to hold them in position.

Each of the laminations 20 and 21 has integrally formed therewith on opposite sides, 30 projections 26. These projections are in the same relative location on each of the laminations 20 and 21 so that when they are stacked, they provide a ridge which may be used as a fulcrum for a purpose which will be set forth hereinafter. 35

As illustrated in Fig. 2 of the drawings, each of the field poles 14 and 15 is provided with a series field winding 27, which is positioned around the pole neck portion 18 of the field poles. The series field windings 27 are arranged to be connected in series circuit relation with the commutating field windings 24, and with the main brushes 28-28, in engagement with a commutator 29 of an armature 30, which it will be understood, is positioned between the pole shoes 40 19 of the field poles 14 and 15. The commutator 29 is also provided with auxiliary brushes 31, which may be short circuited in accordance with the usual practice in the construction of a cross-field generator. 45

In order to reverse the polarity of the generator, a reversing switch, shown generally at 33, is provided and is mounted on the outer frame 10. The reversing switch 33 may be operated by means of a handle 34 which is positioned outside of the frame 10. On operation of the reversing switch 33, the polarity which is applied to the terminals 35 may be reversed. The detailed construction of the reversing switch 33 is set forth in my copending application Serial No. 26,872, filed of even date herewith, and assigned to the assignee of this application. 55

As set forth hereinbefore, the reversing switch 33 is employed to reverse the polarity of the output circuit of the generator. For the purposes of illustration, the output circuit of the generator will be traced in detail as follows. Beginning at the reversing switch 33, the output circuit extends through conductor 36, the series field winding 27 on the field pole 14, conductor 38, the commutating field winding 24 in the upper field pole 14, conductor 39, main brush 28, commutator 29, armature 30, commutator 29, main brush 28, conductor 40, the commutating field winding 24 in 60 70 75 76 77 78 79 80 81 82 83 84 85 86 87 88 the lower main pole 15, conductor 41, the series field winding 21 positioned on the lower main field pole 15 and conductor 42, back to the reversing switch 33.

5 In order to regulate the output of the generator, a pair of magnetic shunt members 44 is provided for bridging the pole shoes 19 of the field poles 14 and 15. As set forth in my aforesaid patent, the shunt members 44 serve to regulate 10 the armature reaction flux, and in this manner, control the output of the generator. As illustrated, the shunt members 44 are provided with grooves 45 which are arranged to be positioned 15 on the ridges formed by the projections 26 in the pole shoes 19 of the lower pole 15. The ridges formed by the projections 26 thus form a fulcrum or axis about which the shunt members 44 may turn. The shunt members 44 may be provided with a number of short circuited turns 46 20 for the purpose set forth in my aforesaid patent.

In order to retain the shunt members 44 in position, bolts 47 are provided which are mounted in suitable threaded openings in the pole shoe 19 of the lower pole 15, and which extend through 25 suitable openings in the outer frame 10. Springs 48 are provided, as shown, for normally biasing the shunt members 44 toward the field poles 14 and 15. For the purposes of more clearly illustrating the invention, the shunt members 44 are 30 shown as having considerable clearance between the sides of the pole shoes 19. However, it is actually desired to reduce this clearance to a minimum, in order to permit the generator to operate at the lowest output capacity.

35 Each of the shunt members 44 is provided with an operating arm 49 having a channel section terminating in a forked end 50, Fig. 5, in which nuts 51 are positioned. The nuts 51 are mounted on a rotatable shaft 52 which is mounted in suitable bearings 53 and 54 in the outer frame 10. A handwheel 55 is provided for rotating the shaft 52. The nuts 51 are oppositely threaded and are arranged to be moved either away from or toward each other on rotation of the shaft 52 by means 40 of oppositely cut threads on the ends thereof. Thus, when the handwheel 55 is rotated in one direction, the nuts 51 are caused to approach each other, thereby permitting the shunt members 44 to be urged toward each other under the influence of the biasing springs 48. When the handwheel 55 is rotated in the other direction, the nuts 51 are simultaneously moved away from each other and the shunt members 44 are moved simultaneously away from the pole shoes 19. In 45 order to limit the movement of the nuts 51 toward each other and to prevent their coming out of the forked ends 50, a sleeve 56 is provided around the shaft 52.

50 Since there is a definite relation between the output capacity of the generator and the position of the shunt members 44, it is unnecessary to provide a meter, such as an ammeter of the moving coil type, to indicate the current that is flowing. Instead, advantage may be taken of 55 this relationship and a corresponding indication may be given as to the output setting of the machine whether it is in operation or not. For this purpose, a pinion 59 is mounted on the shaft 52 and is arranged to rotate therewith. As illustrated in Fig. 5 of the drawings, the pinion 59 is disposed to engage a dial 60, Fig. 6, which is provided with teeth in the periphery thereof. The dial 60 is mounted for rotation inside of the outer frame 10 and has provided thereon two 60 scales 61 and 62, indicating the output rating

of the generator for different positions of the shunt members 44. The scale 61 indicates the current output of the generator when the output voltage, for example the voltage across a welding arc, is maintained at 20 volts. The scale 62 5 provides a corresponding indication when the voltage across the load circuit is 40 volts. In order to view the dial 60, a window 63 is provided in the outer frame 10, as illustrated. As shown, the window 63 is provided in the outer frame 10 10 with suitable indexes corresponding to the different voltage ratings for the two scales 61 and 62.

In the lower output range of the generator, it is desirable to further increase the reactance of 15 the output circuit, in order to stabilize the operation of the generator at the low currents. For this purpose, I have provided auxiliary pole pieces 65, which are secured to the outer frame 10 by means of bolts 66, and which project inwardly therefrom toward the upper field pole 14, as illustrated in Fig. 2 of the drawings. As shown in Fig. 3 of the drawings, the auxiliary poles 65 may be provided with cut away sections 67 to permit their being positioned around the 25 sets of laminations 11 and to be firmly secured to the outer frame 10.

With a view to providing a more complete magnetic circuit around the series field winding 27 in the low output range, each of the shunt 30 members 44 is provided with an auxiliary magnet shunt member 68, which is secured thereto and which may be magnetically insulated therefrom by means of support members 69 of non-magnetic material, such as brass. Screws 70, 35 Fig. 5, are provided for securing the support members 69 to the shunt member 44 and the auxiliary shunt members 68. The auxiliary shunt members 68 may be provided with slots 71 to permit them to be moved into close proximity to 40 the pole shoe of the upper field pole 14, the slots 71 registering with the ridges formed on the upper pole 14 by the projections 26.

It will be readily understood that a complete magnetic circuit having low reluctance will be 45 provided around the series field winding 27 that is mounted on the upper field pole 14 when the shunt members 44 are positioned in close proximity to the pole shoes 19. When they are moved, for example, to a position which may be illustrated by the dotted lines shown in connection with the shunt member 44 on the right-hand side of the armature 30, the reluctance of the foregoing circuit will be considerably increased, due to the movement of the auxiliary shunt members 68 away from bridging relation between the auxiliary poles 65 and the pole shoe 19 of the upper field pole 14. Furthermore, when the auxiliary shunt members 68 are moved out of bridging 50 relation as set forth, the maximum output capacity of the generator is increased since there is less leakage flux around the series field winding 27 positioned on the upper field pole 14 than would otherwise be the case.

55 Since certain further changes may be made in 65 the foregoing construction and different embodiments of the invention may be made without departing from the scope thereof, it is intended that all matter set forth in the foregoing description or shown in the accompanying drawings shall be 70 interpreted as illustrative and not in a limiting sense.

I claim as my invention:

1. A dynamo-electric machine of the cross-field type comprising, in combination, an outer 75

frame of cast construction, an inner frame forming a part of the magnetic circuit for the machine including a plurality of laminations having the width thereof disposed substantially parallel to the inner wall of said outer frame and secured thereto; a pair of field poles secured to and projecting inwardly from said outer frame to form an additional part of the magnetic circuit of the machine with said laminations, each of said field poles including a plurality of laminations disposed to be stacked to form the pole neck and a portion of the pole shoe, and a plurality of additional laminations disposed to be stacked with said last-named laminations to form the remaining portion of the pole shoe; a series field winding disposed around the pole neck of each of said field poles, an armature having a pair of main brushes connected to said series field windings and a pair of short circuited auxiliary brushes disposed between said field poles, movable magnetic shunt means disposed to bridge said field poles, adjusting means for variably positioning said magnetic shunt means to change the output of the machine, indicating means positioned within said outer frame and operatively connected to said adjusting means for indicating the output capacity of the machine corresponding to the position of said magnetic shunt means, and a window in said outer frame to permit inspection of said indicating means.

2. A dynamo-electric machine of the cross-field type comprising, in combination, an outer frame of cast construction, an inner frame forming a part of the magnetic circuit for the machine including a plurality of laminations having the width thereof disposed substantially parallel to the inner wall of said outer frame and secured thereto; a pair of field poles secured to and projecting inwardly from said outer frame to form an additional part of the magnetic circuit of the machine with said laminations, each of said field poles including a plurality of laminations disposed to be stacked to form the pole neck and a portion of the pole shoe, and a plurality of additional laminations disposed to be stacked with said last-named laminations to form the remaining portion of the pole shoe; a series field winding disposed around the pole neck of each of said field poles, an armature having a pair of main brushes connected to said series field windings and a pair of short circuited auxiliary brushes disposed between said field poles, a pair of magnetic shunt members hinged to opposite sides of one of said field poles and disposed to variably bridge them, adjusting means including a rotatable shaft operatively connected to said shunt members for simultaneously moving them away from or toward said field poles to correspondingly increase or decrease the output of the machine, a pinion disposed to rotate with said shaft, a dial rotatably mounted within said outer frame and provided with teeth in the periphery thereof disposed to engage said pinion, a scale on said dial for indicating the output capacity of the machine corresponding to the position of said shunt members, and a window in said outer frame for observing said scale.

3. A dynamo-electric machine of the cross-field type comprising, in combination, an outer frame of cast construction, an inner frame forming a part of the magnetic circuit for the machine including a plurality of laminations having the width thereof disposed substantially parallel to the inner wall of said outer frame and secured thereto; a pair of field poles secured to

and projecting inwardly from said outer frame to form an additional part of the magnetic circuit of the machine with said laminations, each of said field poles including a plurality of laminations disposed to be stacked to form the pole neck and a portion of the pole shoe, and a plurality of additional laminations disposed to be stacked with said last-named laminations to form the remaining portion of the pole shoe; a series field winding disposed around the pole neck of each of said field poles, an armature having a pair of main brushes connected to said series field windings and a pair of short circuited auxiliary brushes disposed between said field poles, a pair of magnetic shunt members hinged to opposite sides of one of said field poles and disposed to variably bridge them, adjusting means including a rotatable shaft operatively connected to said shunt members for simultaneously moving them away from or toward said field poles to correspondingly increase or decrease the output of the machine, a pair of auxiliary poles carried by said outer frame, said auxiliary poles being positioned on opposite sides of and extending toward said other field pole and disposed to cooperate with said shunt members on operation thereof to positions corresponding to low output settings of the machine for decreasing the reluctance of the magnetic circuit associated with the field winding on said other field pole at said settings, a pinion disposed to rotate with said shaft, a dial rotatably mounted within said outer frame and provided with teeth in the periphery thereof disposed to engage said pinion, a scale on said dial for indicating the output capacity of the machine corresponding to the position of said shunt members, and a window in said outer frame for observing said scale.

4. A dynamo-electric machine of the cross-field type comprising, in combination, an outer frame of cast construction, an inner frame forming a part of the magnetic circuit for the machine including a plurality of laminations having the width thereof disposed substantially parallel to the inner wall of said outer frame and secured thereto; a pair of field poles secured to and projecting inwardly from said outer frame to form an additional part of the magnetic circuit of the machine with said laminations, each of said field poles including a plurality of laminations disposed to be stacked to form the pole neck and a portion of the pole shoe, and a plurality of additional laminations disposed to be stacked with said last-named laminations to form the remaining portion of the pole shoe; a series field winding disposed around the pole neck of each of said field poles, an armature having a pair of main brushes connected to said series field windings and a pair of short circuited auxiliary brushes disposed between said field poles, a pair of magnetic shunt members hinged on opposite sides to one of said field poles and disposed to bridge them, adjusting means including a rotatable shaft operatively connected to said shunt members for simultaneously moving them to change the output of the machine, a pair of auxiliary poles carried by said outer frame, said auxiliary poles being positioned on opposite sides of and extending toward said other field pole, an auxiliary magnetic shunt member carried by and magnetically insulated from each of said shunt members and disposed to cooperate with said auxiliary poles and said other field pole on operation of said shunt members to positions corresponding to low output settings of the machine

to increase the inductance of the output circuit of the machine at said low current settings, a pinion disposed to rotate with said shaft, a dial rotatably mounted within said outer frame and provided with teeth in the periphery thereof disposed to engage said pinion, a scale on said dial for indicating the output capacity of the machine corresponding to the position of said magnetic shunt members, and a window in said outer frame for observing said scale.

5. A dynamo-electric machine of the cross-field type comprising, in combination, an outer frame of cast construction, an inner frame comprising two sets of oppositely disposed laminations secured to said outer frame, all of said laminations being of substantially the same length and the width thereof being disposed substantially parallel to the longitudinal axis of said outer frame; a pair of field poles secured to said outer frame 15 in engagement with the ends of said sets of lamination and projecting inwardly, each of said field poles including a plurality of pole laminations disposed to be centrally stacked to form the pole neck and a portion of the pole shoe, and a 20 plurality of additional pole laminations disposed to be stacked at each end of the field pole and forming the balance of the pole shoe, each of said pole laminations having integrally formed therewith single projections in the pole shoe portion 25 30 on opposite sides thereof to provide ridges; a series field winding disposed around the pole neck of each of said field poles, an armature having a pair of main brushes connected to said series field windings and a pair of short circuited auxiliary brushes disposed between said field poles, 35 a pair of movable magnetic shunt members fulcrumed on the ridges of one of said field poles and disposed to bridge said field poles, adjusting means for variably positioning said magnetic 40 shunt members to change the output of the machine, indicating means positioned within said outer frame and operatively connected to said adjusting means for indicating the output capacity of the machine corresponding to the position 45 of said magnetic shunt means, and a window in said outer frame to permit inspection of said indicating means.

6. A dynamo-electric machine of the cross-field type comprising, in combination, an outer frame of cast construction, an inner frame comprising two sets of oppositely disposed laminations secured to said outer frame, all of said laminations being of substantially the same length and the width thereof being disposed substantially parallel to the longitudinal axis of said outer frame; a pair of field poles secured to said outer frame in engagement with the ends of said sets of lamination and projecting inwardly, each of said field poles including a plurality of pole laminations disposed to be centrally stacked to form the pole neck and a portion of the pole shoe, and a plurality of additional pole laminations disposed to be stacked at each end of the field pole and forming the balance of the pole shoe, each of said pole laminations having integrally formed therewith single projections in the pole shoe portion 55 60 on opposite sides thereof to provide ridges; a series field winding disposed around the pole neck of each of said field poles, an armature having a pair of main brushes connected to said series field windings and a pair of short circuited auxiliary brushes disposed between said field poles, a pair of movable magnetic shunt members fulcrumed on the ridges of one of said field poles and disposed to bridge said field poles, adjusting means including a rotatable shaft operatively connected to said shunt members for simultaneously moving them away from or toward said field poles to correspondingly increase or decrease the output of the machine, a pinion disposed to rotate with said shaft, a dial rotatably mounted within said outer frame and provided with teeth in the periphery thereof disposed to engage said pinion, a scale on said dial for indicating the output capacity of the machine corresponding to the position of said shunt members, and a window in said outer frame for observing said scale.

7. A dynamo-electric machine of the cross-field type comprising, in combination, an outer frame of cast construction, an inner frame comprising two sets of oppositely disposed laminations secured to said outer frame, all of said laminations being of substantially the same length and the width thereof being disposed substantially parallel to the longitudinal axis of said outer frame; a pair of field poles secured to said outer frame in engagement with the ends of said sets of lamination and projecting inwardly, each of said field poles including a plurality of pole laminations disposed to be centrally stacked to form the pole neck and a portion of the pole shoe, and a plurality of additional pole laminations disposed to be stacked at each end of the field pole and forming the balance of the pole shoe, each of said pole laminations having integrally formed therewith single projections in the pole shoe portion on opposite sides thereof to provide ridges; a series field winding disposed around the pole neck of each of said field poles, an armature having a pair of main brushes connected to said series field windings and a pair of short circuited auxiliary brushes disposed between said field poles, a pair of movable magnetic shunt members fulcrumed on the ridges of one of said field poles and disposed to bridge said field poles, adjusting means including a rotatable shaft operatively connected to said shunt members for simultaneously moving them away from or toward said field poles to correspondingly increase or decrease the output of the machine, a pinion disposed to rotate with said shaft, a dial rotatably mounted within said outer frame and provided with teeth in the periphery thereof disposed to engage said pinion, a scale on said dial for indicating the output capacity of the machine corresponding to the position of said shunt members, and a window in said outer frame for observing said scale.

8. A dynamo-electric machine of the cross-field type comprising, in combination, an outer frame of cast construction, an inner frame comprising two sets of oppositely disposed laminations secured to said outer frame, all of said laminations being of substantially the same length and the width thereof being disposed substantially parallel to the longitudinal axis of said outer frame; a pair of field poles secured to said outer frame in engagement with the ends of said sets of lamination and projecting inwardly, each of said field poles including a plurality of pole laminations disposed to be centrally stacked to form the pole neck and a portion of the pole shoe, and a plurality of additional pole laminations disposed to be stacked at each end of the field pole and forming the balance of the pole shoe, each of said pole laminations having integrally formed therewith single projections in the pole shoe portion on opposite sides thereof to provide ridges; a series field winding disposed around the pole neck of each of said field poles, an armature having a pair of main brushes connected to said series field windings and a pair of short circuited auxiliary brushes disposed between said field poles, a pair of movable magnetic shunt members fulcrumed on the ridges of one of said field poles and disposed to bridge said field poles, adjusting means including a rotatable shaft operatively connected to said shunt members for simultaneously moving them away from or toward said field poles to correspondingly increase or decrease the output of the machine, a pinion disposed to rotate with said shaft, a dial rotatably mounted within said outer frame and provided with teeth in the periphery thereof disposed to engage said pinion, a scale on said dial for indicating the output capacity of the machine corresponding to the position of said shunt members, and a window in said outer frame for observing said scale.

9. A dynamo-electric machine of the cross-field type comprising, in combination, an outer frame of cast construction, an inner frame comprising two sets of oppositely disposed laminations secured to said outer frame, all of said laminations being of substantially the same length and the width thereof being disposed substantially parallel to the longitudinal axis of said outer frame; a pair of field poles secured to said outer frame in engagement with the ends of said sets of lamination and projecting inwardly, each of said field poles including a plurality of pole laminations disposed to be centrally stacked to form the pole neck and a portion of the pole shoe, and a plurality of additional pole laminations disposed to be stacked at each end of the field pole and forming the balance of the pole shoe, each of said pole laminations having integrally formed therewith single projections in the pole shoe portion on opposite sides thereof to provide ridges; a series field winding disposed around the pole neck of each of said field poles, an armature having a pair of main brushes connected to said series field windings and a pair of short circuited auxiliary brushes disposed between said field poles, a pair of movable magnetic shunt members fulcrumed on the ridges of one of said field poles and disposed to bridge said field poles, adjusting means including a rotatable shaft operatively connected to said shunt members for simultaneously moving them away from or toward said field poles to correspondingly increase or decrease the output of the machine, a pinion disposed to rotate with said shaft, a dial rotatably mounted within said outer frame and provided with teeth in the periphery thereof disposed to engage said pinion, a scale on said dial for indicating the output capacity of the machine corresponding to the position of said shunt members, and a window in said outer frame for observing said scale.

neck and a portion of the pole shoe, and a plurality of additional pole laminations disposed to be stacked at each end of the field pole and forming the balance of the pole shoe, each of said pole laminations having integrally formed therewith single projections in the pole shoe portion on opposite sides thereof to provide ridges; a series of field winding disposed around the pole neck of each of said field poles, an armature having a pair of main brushes connected to said series of field windings and a pair of short circuited auxiliary brushes disposed between said field poles, a pair of movable magnetic shunt members fulcrumed on the ridges of one of said field poles and disposed to bridge said field poles, adjusting means including a rotatable shaft operatively connected to said shunt members for simultaneously moving them away from or toward said field poles to correspondingly increase or decrease the output of the machine, a pair of auxiliary poles carried by said outer frame, said auxiliary poles being positioned on opposite sides of and extending toward said other field pole, an auxiliary magnetic shunt member carried by and magnetically insulated from each of said shunt members and disposed to cooperate with said auxiliary poles and said other field pole on operation of said shunt members to positions corresponding to low output settings for the machine to increase the inductance of the output circuit of the machine at said low current settings, a pinion disposed to rotate with said shaft, a dial rotatably mounted within said outer frame and provided with teeth in the periphery thereof disposed to engage said pinion, a scale on said dial for indicating the output capacity of the machine corresponding to the position of said shunt members, and a window in said outer frame for observing said scale.

40 9. A field pole for a dynamo-electric machine comprising, in combination, a plurality of laminations disposed to be contiguously stacked to form the pole neck and a portion of the pole shoe, and a plurality of additional laminations disposed to be contiguously stacked with said first-mentioned laminations and forming the remaining portion of the pole shoe.

50 10. A field pole for a dynamo-electric machine comprising, in combination, a plurality of laminations disposed to be solidly stacked to form the pole neck and the central portion of the pole shoe, and a plurality of additional laminations disposed to be stacked adjacent to said first-mentioned stack of laminations to increase the length of the pole shoe, said laminations having integrally formed projections to provide a fulcrum for a movable shunting member.

55 11. A field pole for a dynamo-electric machine comprising, in combination, a plurality of laminations disposed to be centrally stacked in the pole and forming the pole neck and a portion of the pole shoe, and a plurality of additional laminations disposed to be stacked at each end of the field pole and forming the remainder of the pole shoe.

65 12. A field pole for a dynamo-electric machine comprising, in combination, a plurality of laminations disposed to be centrally stacked in the pole and forming the pole neck and a portion of the pole shoe, and a plurality of additional laminations disposed to be stacked at each end of the field pole and forming the remainder of the pole shoe, each of said laminations having integrally formed therewith a projection in the 70 pole shoe portion in the same relative position

as on the other laminations to provide a fulcrum for a movable shunting member.

13. A field pole for a dynamo-electric machine comprising, in combination, a plurality of laminations disposed to be centrally stacked in the pole, each of said laminations having a pole neck portion and a pole shoe portion, a plurality of additional laminations disposed to be stacked at each end of the field pole, the entire portion of each of said additional laminations corresponding to the pole shoe portions of said first-mentioned laminations, and means for securing said laminations in stacked relation.

14. A field pole for a dynamo-electric machine comprising, in combination, a plurality of laminations disposed to be centrally stacked in the pole, each of said laminations having a pole neck portion and a pole shoe portion, a plurality of additional laminations disposed to be stacked at each end of the field pole, the entire portion of each of said additional laminations corresponding to the pole shoe portion of said first-mentioned laminations, and means for securing said laminations in stacked relation, the pole shoe portion of each of said laminations being provided with an integrally formed projection on the opposite ends thereof in the same relative position on all of said laminations to provide fulcrums for movable shunting members.

15. A frame for a dynamo-electric machine comprising, in combination, an outer frame disposed to support the field structure of the machine, and an inner magnetic circuit for the machine, said inner magnetic circuit comprising two oppositely disposed sets of laminations secured within the outer frame independently of said field structure, all of said laminations being of substantially the same length and the width thereof being disposed substantially parallel to the longitudinal axis of said outer frame.

40 16. In a magnetic circuit for a dynamo-electric machine, a plurality of oppositely disposed sets of substantially identical rectangular laminations stacked to substantially form an arc of a cylinder thereby causing at least one end of said laminations to be stepped, said sets of laminations being secured within a field member supporting structure independently of said field members.

45 17. A dynamo-electric machine of the cross-field type comprising, in combination, a pair of field poles having integral projections thereon, an armature having main and auxiliary brushes disposed between said field poles, a pair of magnetic shunts resiliently maintained in engagement with opposite sides of one of said field poles for variably bridging them, said resilient means biasing said magnetic shunts toward the other of said field poles, and adjusting means comprising a single threaded rod operatively connected to said shunts for simultaneously moving them away from said field poles against the biasing force of said resilient means to increase the output of the machine.

50 18. A dynamo-electric machine of the cross-field type comprising, in combination, a frame, a pair of field poles carried by said frame, an armature having main and auxiliary brushes disposed between said field poles, movable magnetic shunt means disposed to bridge said field poles, adjusting means for variably positioning said magnetic shunt means to change the output of the machine, and auxiliary pole means carried by said frame, said auxiliary pole means extending toward one of said field poles and

disposed to cooperate with said magnetic shunt means on operation thereof to positions corresponding to low output settings for the machine.

19. A dynamo-electric machine of the cross-field type comprising, in combination, a frame, a pair of field poles carried by said frame, an armature having main and auxiliary brushes disposed between said field poles, a magnetic shunt member hinged to one of said field poles and disposed to bridge them, adjusting means for variably positioning said shunt member to change the output of the machine, and an auxiliary pole carried by said frame, said auxiliary pole extending toward the other of said field poles and disposed to cooperate with said shunt member on operation thereof to positions corresponding to low output settings for the machine.

20. A dynamo-electric machine of the cross-field type comprising, in combination, a frame, a pair of field poles carried by said frame, an armature having main and auxiliary brushes disposed between said field poles, a pair of magnetic shunt members hinged to one of said field poles and disposed to bridge them, adjusting means for variably positioning said shunt members to change the output of the machine, and a pair of auxiliary poles carried by said frame, said auxiliary poles being positioned on opposite sides of and extending toward said other field pole and disposed to cooperate with said shunt members on operation thereof to positions corresponding to low output settings for the machine.

21. A dynamo-electric machine of the cross-field type comprising, in combination, a frame, a pair of field poles carried by said frame, an armature having main and auxiliary brushes disposed between said field poles, movable magnetic shunt means disposed to bridge said field poles, adjusting means for variably positioning said magnetic shunt means to change the output of the machine, auxiliary pole means carried by said frame and extending toward one of said field poles, and additional magnetic shunt means carried by and magnetically insulated from said first-mentioned shunt means and disposed to cooperate with said auxiliary pole means on operation of said first-mentioned shunt means to positions corresponding to low output settings for the machine to increase the inductance of the output circuit of the machine.

22. A dynamo-electric machine of the cross-field type comprising, in combination, a frame, a pair of field poles carried by said frame, an armature having main and auxiliary brushes disposed between said field poles, a magnetic shunt member hinged to one of said field poles and disposed to bridge them, adjusting means for variably positioning said shunt member to change the output of the machine, an auxiliary pole carried by said frame and extending toward the other of said field poles, and an auxiliary magnetic shunt member carried by and magnetically insulated from said shunt member and disposed to cooperate with said auxiliary pole and said other field pole on operation of said shunt member to positions corresponding to low output settings for the machine to increase the inductance of the output circuit of the machine.

23. A dynamo-electric machine of the cross-field type comprising, in combination, a frame, a pair of field poles carried by said frame, an armature having main and auxiliary brushes disposed between said field poles, a pair of magnetic shunt members hinged to one of said field poles and disposed to bridge them, adjusting means for

variably positioning said shunt members to change the output of the machine, a pair of auxiliary poles carried by said frame, said auxiliary poles being positioned on opposite sides of and extending toward said other field pole, and an auxiliary magnetic shunt member carried by and magnetically insulated from each of said shunt members and disposed to cooperate with said auxiliary poles and said other field pole on operation of said shunt members to positions corresponding to low output settings for the machine to increase the inductance of the output circuit of the machine.

24. In a dynamo-electric machine of the cross-field type having a pair of field poles and an armature interposed therebetween the combination of an integral ridged projection on a side of at least one field pole, a magnetic shunt resiliently positioned in engagement with a ridged projection of a field pole on one side of said armature for varying the reaction flux thereof, and means for adjusting said shunt.

25. In a dynamo-electric machine of the cross-field type having a pair of field poles and an armature interposed therebetween the combination of field poles having integral ridged projections, a pair of magnetic shunts resiliently retained in pivotal engagement with said projections on opposite sides of a field pole, and a single adjusting means comprising a threaded shaft operatively connected to an end of each of said shunts for simultaneously moving said end toward or away from a field pole to correspondingly decrease or increase the output of the machine.

26. A magnetic structure for a dynamo-electric machine comprising, in combination, an outer supporting frame, a plurality of field pole members secured to and projecting inwardly from said outer frame, and an inner main magnetic circuit comprising separate sets of similar laminations disposed between adjacent field pole members and independently secured to said outer frame, the width of said laminations being essentially parallel to the axis of said machine, and adjacent ends of successive sets of laminations being separated from one another.

27. A structure for a dynamo-electric machine comprising, in combination, an outer frame member, a plurality of field pole members each comprising a plurality of laminations stacked to form a pole neck and a pole shoe and a plurality of additional laminations stacked adjacent to the first-mentioned stack to increase the face area of said pole shoe, said field pole members being secured to said outer frame, and an inner magnetic circuit comprising sets of similar rectangular laminations independently secured within the outer frame with the width of a lamination being essentially parallel to the axis of the machine, and the length of a lamination being in arcuate relation between a pair of adjacent field pole members.

28. The combination in a structure for a dynamo-electric machine comprising a rigid supporting frame, a plurality of field pole members supported by said frame, and a magnetic circuit comprising separate sets of substantially identical laminations disposed to be secured within the supporting frame in arcuate relation between adjacent field pole members, adjacent ends of successive sets of laminations being clamped in spaced relation between a field pole member and said frame.

29. A dynamo-electric machine of the cross-field type, comprising, in combination, a frame, a

pair of main field poles, an armature with main and auxiliary brushes, and adjustable means in shunt with one of said main field poles and said frame for varying the reluctance of the path of the leakage flux between a main pole and the frame to control the output of the machine.

30. A dynamo-electric machine of the cross-field type, comprising, in combination, a frame, a pair of main field poles, an armature with main and auxiliary brushes, a movable member disposed in shunt relation with one of the main field poles and the frame operable to vary the reluctance of the leakage flux path between said main field pole and said frame to control the output of the machine, and means for adjusting the position of the movable member.

31. A dynamo-electric machine of the cross-field type, comprising, in combination, a frame, a pair of main field poles, an armature with main and auxiliary brushes, adjustable means in shunt with a main field pole and the frame operable to vary the output of the machine by varying the reluctance of the leakage flux path between the

main field pole and frame, means including a rotatably mounted shaft for actuating the adjustable means, and indicating means actuated by said shaft for indicating the output of the machine in accordance with the position of said adjustable means.

32. A direct-current generator of the cross-field type, comprising, in combination, a frame, a pair of main field poles secured within the frame opposite one another, an armature rotatably mounted coaxially with the frame having main and auxiliary brushes, movably mounted means in shunt with one of the main field poles and frame for controlling the output of the generator by varying the reluctance of the leakage flux path between the main field pole and the frame, means for actuating the movably mounted means to different positions, and an indicating dial actuated by said means for indicating the output of the generator in accordance with the position of the movably mounted means.

JOHN H. BLANKENBUEHLER.
